UNITED STATES PATENT OFFICE.

ELBERT J. BURRELL, OF AETNA, TENNESSEE.

APPARATUS FOR DISTILLING WOOD.

SPECIFICATION forming part of Letters Patent No. 363,313, dated May 17, 1887.

Application filed December 9, 1886. Serial No. 221,136. (No model.)

To all whom it may concern:

Be it known that I, ELBERT J. BURRELL, a citizen of the United States, residing at Aetna, in the county of Hickman and State of Tennessee, have invented certain new and useful Improvements in the Manufacture of Charcoal and Distillation of Wood Products; and I do declare the following to be a full, clear, and exact description of the invention, such as will enable others skilled in the art to which it appertains to make and use the same, reference being had to the accompanying drawings, and to letters of reference marked thereon, which form part of this specification.

15 In the drawings, Figure 1 is a plan view embodying my invention, showing a battery of ovens or kilns and two series or groups of condensers with the necessary connections. Fig. 2 is a vertical section of one kiln, showing the connection of the kiln with the gas-flues; and Fig. 3 is a side view of the condensers, fans, blowers, and gas-flues.

Like letters refer to like parts wherever they occur.

25 My invention relates to the utilization of the non-condensable and uncondensed gases and vapors given off in the carbonization of wood, and the mixture of said gases with a suitable proportion of oxygen from the atmosphere for 30 combustion, and to the handling of said gases, with the necessary power completely controlling the same.

It also relates to the handling of the condensable gases emanating from the charcoal kilns by drawing or exhausting the same through a series or group of condensers and forcing or propelling the same through another separate set or group of condensers.

In the drawings, A indicates a kiln or battery of any suitable number of kilns or ovens for the carbonization of wood, built upon any approved plan and of any suitable material—preferably of brick laid in cement mortar. Each is provided with a door, a, for charging 45 the wood, a furnace, b, for burning solid or gaseous fuel, and a distributor of heat, a', in the center of the base of the kiln, for introducing the heat for carbonization of the wood.

40 c indicates the opening, vent, or flue for the exit of the condensable vapors or gases emanating from the kiln during carbonization, which pass into a special vertical chimney, d,

arranged beside each kiln or oven, and which is provided with a cap. From this flue d the uncondensed gases pass through valved branch 55 flue h into gas-main i, which conveys them to the first series or groups of condensers, B B, located on platform P. These gases pass through all the condensers B B, alternately entering and passing out at the top and bottom 60 of the same through connecting gas-mains K K.

D is a fan or pressure-blower, which draws the said gases through condensers B B, gas-main i, and branch main h, and drives or propels them through connecting-flues K K and 65 through the second series or group of condensers, C C, the connecting-mains being alternately applied at top and bottom, as in the case of condensers B B.

E is a vertical exit-chimney, into which the 70 uncondensable and uncondensed and inflammable gases escape after passing through all the condensers. It is provided with a valve for regulating exit of gases.

F is a powerful fan or pressure-blower, 75 which draws the said uncondensed inflammable gases from chimney E through connecting gas-main m m into main return gas-flue g, which is laid under surface of ground n, and thus also drives these gases into return branch 80 flue f and valved copper pipe and elbow e into the furnace H, where they are consumed.

G is an air-inlet in gas-main m, between chimney E and pressure-blower F, which has 85 a valve that controls the introduction of atmospheric air into and its admixture with the uncondensable inflammable gases in any required quantity or volume on their passage toward the furnace b, the purpose being to produce efficient combustion.

90 The apparatus being such as specified above, the operation is as follows: The kiln or kilns A having been charged with wood through the door, the latter is sealed, and wood is also introduced into furnace H and fired. The 95 draft of chimney d and the admission of air through vent-holes in the kiln (not shown) fan and feed the incipient fire, and smoke and fumes escape through chimney d. After the process of carbonization is fairly started 100 and the wood gases are being evolved, fan D is started. The draft is communicated through main gas-flue i, branch flue h, chimney d, and gas vent or flue c in the kiln, and the uncon-

densed gases from the kiln or oven are drawn through the first series or group of condensers, B B, and propelled or driven by fan D through the second series or group of condensers, C C, 5 then through communicating flues K K into exit-chimney E, and if not needed for fuel are allowed to escape upward through the same. By the action of pressure-blower F, however, the uncondensable and inflammable gases, when 10 needed for fuel in furnace b, are drawn from chimney E, when its valve is closed through gas-main m and driven through return gas-main g, branch main f, and valved branch copper pipe e into furnace b and there consumed. While the gases are thus being conveyed into the furnace b, the air-valve G in gas-main m is kept open, and a sufficient supply of oxygen is thus introduced and mixed with said gases in suitable proportion to produce 15 thorough and instantaneous combustion. The heat of such burning gases passes through distributor a' and carbonizes the wood, and produces an additional supply of uncondensed gases in the kiln.

20 The kiln K has no special air-inlet and no air is admitted into it during carbonization, the kiln being under pressure, except as an admixture to the uncondensable inflammable gases in special proportionate combination 25 by action of the thoroughly-controlled air-valve G, as above described. Through the exhaust and pressure of fan or blower D, the uncondensed gases from the kiln are passed through the two series of condensers B B and C C, 30 where the pyroligneous acid is eliminated, and the uncondensable gases remain, which are passed, through the action of pressure-blower F, through return gas-main g, after admixture of oxygen of the air by valve G, into the furnace b, to be used as fuel.

35 Wood or other solid fuel is used in the furnace b only to start the firing and during the progress of carbonization occasionally in small quantities to accelerate combustion and 40 to increase the heat, gas-fuel, with a proper admixture of air, constituting the main and at times the only fuel in the furnace b.

The advantages of my invention are the 45 equalizing, regulating, and harmonizing of the 50 action of the gases, by combined suction and pressure when passing from the kiln or oven to the condensers, by being exhausted or drawn through a portion or group of the condensers and propelled into or pushed into another portion or group of condensers, thus regulating and equalizing the flow of gas, and preventing any choking, stoppage, or check of same, or the too rapid flow of same, while the uncondensable inflammable gases are simultaneously

being acted upon by a pressure-blower, drawing and exhausting the gases from the second series or group of condensers, thus producing a gradual, steady, and thoroughly-controllable motion of the gas through all the condensers and the same steady pressure upon all the gas-mains by the thoroughly regulated and controlled rotary motion of the fans and blowers. 60

65 Another advantage of my invention is the introduction of the air-valve G, by which any necessary amount of air (or oxygen) can be incorporated or mixed with the gases needed for combustion, which supply of air can be thoroughly controlled at will. When desirable, the gas can be shut off from return gas-main g and allowed to escape through chimney E altogether or in any desirable quantity, and the supply of air can also, if necessary, be entirely 70 shut off. Thus the performance of the carbonizing of wood, the condensation of the gases and vapors from the kiln, the production of 75 pyroligneous acid, and the application of uncondensable and inflammable gases from the condensers as fuel for supplying the heat for 80 the carbonization of wood in the kiln are systematized, simplified, and regulated at will, 85 and the gas is prepared for proper combustion during its passage to the kiln, without any special air-inlet into the latter.

90 Having thus described my invention, what I claim is—

1. The combination of the following elements: a closed charcoal-kiln, condensers, and a fan connected therewith, a main extending from the last condenser of the series to the furnace of the kiln, and having a valved inlet for regulating admission of atmospheric air, and a second fan, located between the air-inlet and the furnace, for the purpose of exhausting or drawing the uncondensed gases from the last condenser and forcing or propelling them, admixed with air, forward to the furnace, substantially as shown and described. 95

100 2. The combination, with a closed charcoal-kiln, of two separate groups or series of condensers, a fan or blower located between the same for exhaust and pressure, a chimney connected with the condensers and provided with a valve for closing it, a main connected with the said chimney and leading to the kiln-furnace, an adjustable air-inlet valve or damper 105 in said main for the mixture of air and gas, and a fan or pressure-blower connected with said main, all substantially as shown and described, to operate as specified. 110
